ATTORNEY

UNITED STATES PATENT OFFICE.

ALICE CLARK, OF CHASE CITY, VIRGINIA.

TICKET-HOLDER.

1,252,237.

Specification of Letters Patent. Patented Jan. 1, 1918.

Application filed September 29, 1916. Serial No. 122,901.

To all whom it may concern:

Be it known that I, ALICE CLARK, a citizen of the United States, residing at Chase City, in the county of Mecklenburg and 5 State of Virginia, have invented certain new and useful Improvements in Ticket-Holders, of which the following is a specification.

My invention relates broadly to sign fasteners and more particularly has reference to a price ticket holder.

The primary aim and object of the present invention resides in the provision of novel means arranged on the ends of a flexible sign, such as a price ticket, for removably fastening the ticket to an article without injuring the same, the ticket itself serving to hold the fastening means in position.

The invention, as an additional object, 20 contemplates the provision of novel ticket fastening means whereby the ticket is effectively engaged and held so as to consequently facilitate the fastening of the ticket on a garment.

Among the other aims and objects of the invention may be recited the provision of a device of the character mentioned with a view to compactness, the number of parts of 25 which are few, the construction simple, the 30 cost of production low and the efficiency high.

Other improvements and novel details in the construction and arrangement of the various parts of the apparatus will be brought 35 out more in detail in the description to follow, which, for a clear understanding of the invention, should be considered in connection with the accompanying drawings, forming a part hereof, and wherein is disclosed, for the purpose of illustration, a convenient and satisfactory embodiment of the 40 invention. It is to be noted, in this connection, that minor changes in the construction and arrangement of the parts may be 45 made without departing from the spirit of the invention or the principle of operation of the various parts.

In the drawings:—

Figure 1 is a front elevation of my invention.

Fig. 2 is a transverse section taken on line 2—2 of Fig. 1 in the direction in which the arrow points.

Fig. 3 is a transverse section taken on line 55 3—3 of Fig. 1 in the direction in which the arrow points.

Fig. 4 is a rear elevation of my invention, and

Fig. 5 is a perspective.

Similar characters of reference are employed in all of the above described views to indicate corresponding parts.

Referring now, more particularly, to the accompanying drawings I provide a sign which may be and preferably is a price 60 ticket 1 and along the respective ends of which are arranged my improved fasteners or holders generally designated by the numeral 2 for securing the ticket to a garment or other article 3.

In the present instance each of the fasteners or holders consists of a single strip of relatively flat metal as indicated by the numeral 4, the respective ends of the strip being enlarged while spurs 5 are struck out 70 therefrom and arranged to be engaged in the ticket 1 adjacent the upper and lower ends and the adjacent side. It is to be noted that the spurs 5, when fastened in the ticket, extend toward each other. Spurs 6 also extend 80 laterally and in spaced relation to each other from one marginal edge of the strip and are adapted to also extend laterally from the edge of the ticket and engage the garment 3.

In use, I employ two of the fasteners and connect them, in the manner described, to the respective side edges of the ticket 1 so that the spurs 6 extend laterally of the side edges of the ticket. The spurs 6 of one fastener are engaged in the garment 3 in the manner indicated in the drawing while the flexible ticket is flexed so as to allow the engagement of the spurs 6 of the other fastener with the garment. It is to be understood that although the ticket itself is flexible, it is rigid enough to retain the spurs 6 in position subsequent to the flexing thereof. To remove the ticket it is only necessary to engage the ticket and bend or flex it intermediate the ends and at the same time draw the spurs 6 of one of the fasteners from engagement with the garment 3 whereupon the spurs of the other fastener may be readily removed as is obvious.

As many changes could be made in the above construction and many apparently widely different embodiments of this invention could be made without departing from the scope thereof, it is intended that all matter contained in the above description or shown in the accompanying drawings shall

be interpreted as illustrative and not in a limiting sense. It is also to be understood that the language used in the following claim is intended to cover all of the generic 5 and specific features of the invention herein described and all statements of the scope of the invention, which as a matter of language, might be said to fall therebetween.

Having described my invention, what I 10 claim as new and desire to secure by Letters Patent is:—

As a new article of manufacture, a ticket holder made from a single piece of flat material having an elongated body with spaced 15 spurs formed on one lateral edge near the

ends of the body to removably engage with a ticket, and spaced spurs struck up from the material of the body adjacent its ends so that said latter spurs project from the body at right angles to the spurs on the lateral 20 edge to removably engage with a fabric, said body being substantially inflexible and maintained flat at all times.

In testimony whereof I affix my signature in presence of two witnesses.

MRS. ALICE CLARK.
